Atkins

UNITED STATES PATENT OFFICE.

JOHN B. WATLING, OF CHICAGO, ILLINOIS.

AMUSEMENT APPARATUS.

Application filed November 22, 1923. Serial No. 676,251.

This invention relates to amusement apparatus of the coin-controlled type but more particularly to fortune-telling devices in which the operator may select any one of a number of available questions and the mechanism will display an answer to the question selected.

The primary object of the present invention is to provide a novel and ingenious device of the type described which is simple in construction and capable of withstanding hard use.

The particular embodiment of my invention which I have chosen to illustrate the principles thereof is incorporated in a weighing scale of well-known type and the mechanism is so constructed and arranged that a single coin will cause the apparatus to register the weight of the operator and answer a selected question.

The many other objects and advantages of my invention will be better understood by reference to the following specification when considered in connection with the accompanying drawings, in which:

Fig. 1 is a front elevation of a portion of the apparatus, and

Fig. 2 is a rear elevation of the apparatus with wall of casing removed, showing the fortune-telling mechanism.

Referring to the drawings, the apparatus is substantially enclosed in a casing 10 provided with an arcuate opening or window 11 to expose the weighing scale dial 12. The coin slot is located at 13. A window 14 exposes a segment of the inner or question ring 15 on the revolute dial 16. A similar window 17 exposes a segment of the outer or answer ring 18 on the dial 16. An operating knob 19 is connected to the outer end of a revolute shaft 20 projecting through the front of the casing.

The weighing mechanism is not shown in detail as this mechanism forms no part of the present invention. A coin inserted in the slot 13 actuates a rock arm 21 to release the ratchet or toothed wheel 22 controlling this mechanism. One extremity of this rock arm is provided with a coin pocket 23 disposed beneath the lower end of the chute 24 connected to the coin slot. The weight of the coin causes the pocketed end of this arm to swing downwardly and lift the pawl 25 from the ratchet wheel. The continued downward movement of this arm permits

the coin to drop from the pocket into the coin chute 26.

At the bottom of the chute 26 is a second coin pocket 27 on the extremity of a rock arm 28, pivotally mounted on the supporting frame 29 at 30. This arm 28 is normally held with the pocket 27 in the position indicated in solid lines in Fig. 2 by the spring 31 and the counterbalancing weight 32, the latter being mounted on the outer end of an extension 33 of the arm. A stop 34 projects laterally from this arm and is normally held in position to engage a catch 35 on the inner end of a lever 36. This catch is pivotally connected to the lever at 37. A spring 38 normally holds the inner end of the catch 35 against the stop pin 39 on the lever 36. The catch 35 prevents the lever 36 from swinging downwardly when the stop 34 is in its normal position, as indicated in Fig. 2. Rocking of the arm 28 in the manner described, releases the stop from the catch 35. As soon as a coin has been emptied from the pocket 27 into the coin box 40, the spring 31 and the counterweight 32 cause the arm 28 to return to its normal position. The upward movement of the lever 36 past the stop 34 is permitted by the rocking of the catch 35 upon its pivot.

The lever 36 is pivotally connected to the frame 29 at 41 and a second lever 42 is connected to the inner end of the lever 36 to form therewith substantially a bell crank. The outer extremity 43 of this lever 42 is bent forwardly and then inwardly and carries at its outer end a shutter 44 to normally close the window 17 and conceal the answer dial. A guide 45 is provided for the lever 42 upon an extension 46 of the frame 29.

A sprocket 47 is secured upon the shaft 20 within the casing and a driving chain 48 operatively connects this sprocket with a sprocket 49 revolvably mounted on the shaft 50. A spider 51 is secured to the sprocket 49 and this spider carries the dial 16 on which are inscribed the questions and answers, as previously described.

A short lever 52 is pivotally mounted on the frame at 53 and one end of this lever is provided with a roller 54 which operates upon the periphery of the sprocket 49 and is held in yielding engagement therewith by the spring 55. The sprocket acts as a cam and the roller as a cam follower so that rotation of the sprocket imparts a rocking mo-

tion to the lever 52. An arm 56 projects downwardly from the lever 52 and has its lower extremity connected to the lever 42 by a link 57. The forcing outwardly of the 5 roller 54 by a tooth of the sprocket causes the lever 42 to swing in a clockwise direction and to move the shutter 44 to closed position. The catch 35 permits the outer end of the lever 36 to swing past the stop 34 but prevents the dropping of the lever past this stop when the roller 54 enters the next depression between the teeth on the sprocket 49. When the stop 34 is withdrawn from the catch 35 by the downward movement of the 10 arm 28 in the manner described, the lever 42 swings in a counterclockwise direction by force of gravity and moves the shutter 44 to bring the opening 58 in this shutter into registration with the opening or window 15 17 in the front panel or mirror of the casing 10, exposing the particular answer to the question exhibited through the window 14. This counterclockwise movement of the lever 42 is permitted by the slot 59 in the link 57, and the extent of such movement is determined by the guide 45. The lever 42 is shown in solid lines (Fig. 2) in closed shutter position and the open shutter position is indicated in dot. The slot 59 in the link 30 57 also permits movement of the arm 56 caused by the continuous rotation of the shaft 20 without materially moving the lever 42 when this lever has been brought to closed shutter position. A spring-actuated 35 chain-tightening device 60 is pivotally mounted on the frame 29 as 61, the roller or idler pulley 62 maintaining constant pressure upon the chain, as indicated in Fig. 2.

In the present embodiment of the invention, there are thirty-two teeth on the 40 sprocket 49 connected to the dial 16. The ring 18 containing the answers is divided into thirty-two equal segments, corresponding to the number of teeth on the sprocket 45 49, a different answer being placed in each segment. The question ring 15 is similarly 50 divided into thirty-two equal segments with one question in each segment, but there are only eight different questions, each quadrant 55 having the same series of questions and arranged in the same order. It will therefore be evident that four answers are provided for each question. The answers are so prepared and located that an appropriate one 60 will be exposed for each question asked. I prefer to have the number of answers a multiple of the number of different questions, so that a variety of answers may be provided for each question, but this is not necessary.

In the operation of the device, the knob 65 is turned to the right until a question is exposed which the operator desires to ask. An appropriate answer to this question is at the same time brought into registration with the window 17 but remains concealed until

the operator has dropped a coin in the slot 13. The descending coin in turn renders the weighing apparatus operative and causes the shutter 44 to be moved to open position, exposing the answer. The pointer 63 of 70 the weighing apparatus indicates the weight on the dial 12 in the usual manner. As soon as the knob is turned again to the right to change the question, the shutter 44 is tripped and returns to its normal position, closing 75 the answer opening.

It will be readily evident that this device is amusing and offers an inducement to the public to use the weighing scale. The construction is simple, strong, and fully capable 80 of withstanding the hard usage to which such a device is subjected. The dial may be readily changed at any time to provide a new set of questions and answers. The arrangement of the questions and answers 85 upon the same dial is advantageous.

I am aware that many changes may be made in the construction and arrangement of parts without departing from the spirit 90 of my invention, and I reserve the right to make all such as fairly fall within the scope of the following claims.

I claim as my invention:

1. In a device of the class described, a 95 housing having two openings therein, a rotatable disk member arranged within the housing and having portions visible through the openings, means for manually operating said disk member, a shutter, a coin-controlled trip device for holding the shutter 100 in position to obstruct the view of the disk member through one opening, said trip device operable upon insertion of a coin to release the shutter, and means actuated upon rotation of the disk member adapted to re- 105 engage the shutter with said trip device after each opening operation.

2. In an apparatus of the class described, the combination of a casing provided with a plurality of windows therein, a manually 110 revoluble dial in the casing having a series of questions thereon adapted to be successively brought into position before one of said windows and a series of answers on said dial adapted to be successively brought 115 into position before another of said windows, a shutter adapted to normally conceal the answer in said position and adapted to move by gravity to expose the answer, means for releasing the shutter to permit movement thereof by gravity to expose the answer, and means to move the shutter to closed position upon presenting another question before a window.

3. In an apparatus of the class described, the combination of a casing provided with a plurality of windows therein, a revoluble dial within the casing having a series of questions thereon adapted to be successively brought into position before one of said 120 windows, a shutter adapted to normally conceal the answer in said position and adapted to move by gravity to expose the answer, means for releasing the shutter to permit movement thereof by gravity to expose the answer, and means to move the shutter to closed position upon presenting another question before a window.

- windows, a knob for manually rotating the dial and a series of answers on said dial adapted to be successively brought into position before another of said windows, a shutter adapted to normally conceal the answer in said position and adapted to move by gravity to expose the answer, coin-controlled means for locking the shutter in the concealing position and adapted to be released upon the insertion of a coin to permit movement of the shutter by gravity to expose the answer, and means to return the shutter to a concealing position upon operation of the knob.
- 15 4. In apparatus of the class described, the combination of a casing provided with a plurality of windows therein, a manually revoluble dial in the casing having a series of questions thereon adapted to be successively brought into position before one of said windows and a series of answers on said dial adapted to be successively brought into position before another of said windows, a shutter adapted to normally conceal the answer in said position and adapted to move by gravity to expose the answer, coin controlled means for locking the shutter in concealing position and adapted to release the shutter to permit movement thereof by gravity to expose the answer upon insertion of a coin, and means co-operable between the shutter and the dial to cause the shutter to move to closed position to conceal the answer, said means also permitting rotation of the dial independently of the shutter and coin-controlled mechanism when the shutter is in a closed position.

JOHN B. WATLING.
